HEARTH KIT

Lewen R. Nelson, Peoria, Ill.

Application March 6, 1947, Serial No. 732,885

4 Claims. (Cl. 211—60)

1

This invention is directed to improvements in hearth kits, or that type of device wherein the handles of hearth tools are all supported in upright positions.

More particularly, the invention is directed to improvements in such a structure as illustrated in Letters Patent No. 2,230,667 issued to me February 4, 1941.

An object is to simplify the construction of a hearth kit by using a minimum of material, and simplify the work of assembling accurately fabricated parts thereof, together with a saving of time in such work.

Another object is to provide as a guide for the several hearth tools, an insertable member for a hearth kit that can be readily and quickly fabricated, said member replacing portions that have heretofore been faulty by reason of being produced by casting methods.

Further, an object is to provide a member that can be produced from material of ribbon form in a continuous manner and by which also any one member is of perfect form ready for placing in the kit.

Other objects and advantages will appear in the following specification aided by the appended drawings forming part hereof.

Figure 1 is a plan of a kit of which the present invention is a part.

Figure 2 is likewise a plan of a kit except for the top portion shown in Figure 1.

Figure 3 is a transverse section of the kit, in elevation showing the structure of the present invention, produced on line 3—3 of Figures 1 and 2.

Figure 4 illustrates in perspective a member shown in both Figures 2 and 3.

Figures 5 and 6 show in perspective two separate parts shown in Figure 2.

Figure 7 shows also in perspective a structure as part of the under side of a top portion of the kit, said portion here being shown in an inverted position, and

Figure 8 is a part of the upper portion of the kit in sectional elevation as produced on line 8—8 of Figure 1.

In order to set forth the present invention the drawings necessarily involve some of the parts illustrated in my Letters Patent above referred to, and such parts will be identified herein as an assistance in describing the present advancement.

In the named figures, 1 designates the base portion of the kit, 2 the top portion, and 3 a jacket spacing apart, and abutting those said portions, said jacket resting upon a ledge 3³, Figure 3, and itself receiving the top 2. As shown in plan in the said Figure 2 the jacket forms an enclosure, the spaced ends 3' thereof engaging upstanding spaced lugs 1² on the base, their counterparts 2²

depending from the top 2, one of which is indicated in Figure 3, bolts 1³ serving to secure all in rigid relation.

Arising from the base 1 is a receptacle 4 for receiving one of the hearth tools, in this instance the end of a poker 5, shown in Figure 1.

Upstanding from the base is also a socket member 6, Figures 2 and 5, to receive the ends of a tongs 7, Figure 1, while at 8, Figures 2 and 3, a depressed portion 8 of the base acts as a receptacle for a shovel 10, the handle of which is indicated in Figure 1.

The top 2 is provided with openings 11, 12 and 13 therethrough which lie directly above the named receptacle 4, socket member 6 and the shovel position 8, respectively, of the base, and in such positions that the handle rods of the several tools are maintained upright and paralleling each other.

20 Heretofore the top and base members have been made of cast metal. These included extensions on both members adapted to meet and abut on each other as spacing means as well as to form guides, in some instances, for the hearth tools.

25 Disadvantages arose in this method of manufacture due to the fact that assembling operations were difficult and delayed by reason of faulty castings and the necessity of grinding or filing such extensions to proper form.

30 This has been obviated by substituting for the named abutting extensions a simple insertable member of material to be clamped between the base and top and which serves to provide a guide for each of the several tools herein named.

35 In a study of Figures 2, 3 and 4 it will be seen that a ribbon of the desired material is, in this instance, of a general U-form.

40 This member comprises two cheek portions 14, 15 as extensions of a yoke portion 16. Said yoke portion 16, as formed in the present instance, creates a recess of a width equal to the spacing of the ends 3' of the named jacket as clearly shown in Figure 2, such recess being employed for the reception of a suspended brush as a hearth

45 tool, not shown, and said recess lies at what may be termed the rear of the structure below the recess 1' of the top 2, Figures 1 and 3. At each side of the recess the yoke abuts both of the named lugs 1² of the base and abuts, as well, 50 those on the top 2 at 2² before identified, the said member being of a height substantially equal to the distance between the top and the base so that it may be clamped in place, between them.

55 The named cheek 14, in this instance extends forwardly substantially at right angles to the plane of the portion 16 and lies adjacent the socket member 6 for the tongs 7. At the pos-

tion of the latter the cheek is curved throughout substantially its full height as at 14' to form a guide for said tongs in introducing and seating the same. The formed free edge of said cheek terminates behind an upstanding lug 14² of the base for stabilizing purposes.

The material at the bend 14' may be flared near the top if desired, as shown in Figure 4 to receive a depending flange 2³ of the top 2, Figure 8, which lies adjacent the opening 13 in 10 the latter as the tongs position, see Figure 1. This flange also serves as a stabilizer as may be seen.

The opposite cheek 15 likewise extends forwardly, thence at its lower edge curved around the upstanding poker receptacle 4, the upper or top edge also curved around a flange 2⁴, Figure 7, depending from the top at the opening therein for the poker 5. From these positions the cheek extends rearwardly or toward the yoke as at 15', its free extremity abutting the main cheek portion 15 thus holding the two portions 15, 15' in spaced relation to create a full guide for the poker. An upstanding lug 17 on the base assists the poker receptacle in holding the cheek securely.

As is shown in Figure 4, particularly, the rear yoke-portion 16 may conveniently provide a guide for the shovel blade. That is to say, said yoke-portion may be slit at two spaced positions to create a tongue 18, Figures 2, 3 and 4, which tongue when extended being made to lie substantially as shown in Figure 3, its free extremity lying beneath the shovel opening 13 in the top 2. Thus, when the shovel blade is lowered it will be guided by said tongue toward its seating position at 8, the shovel-handle taking up its desired vertical position.

The assembling operation is simple, and quickly completed. After the jacket 3 has been fixed in position on the base the insertable member is placed on the latter in the position described, whereupon the top 2 may be dropped in place since all of the parts are in complete register. The insertion of the bolts 13 secures the whole, thus providing a sturdy structure throughout.

It is to be understood that the specifically described disposal of the insertable member 14, 15, 16 is applied to a kit of the form now manufactured, but that the said member may be otherwise formed to accommodate itself to any tool holding device where the receptacles for tools may have other positions, or where, also, the stabilizing parts may be other than described and shown herein.

It is conceivable that kits for this or like purposes may be constructed when registering openings for tools or may lie at other positions and for this reason it is not the intention to be confined to the particular form now employed.

An advantage in producing any such pliable member is that it may be rapidly and accurately made by machine, and since it is accurate in measurement and finish it is clear that fast assembling is assured.

I claim:

1. An article of manufacture consisting of a relatively long and narrow ribbon-like member formed to include two cheek portions spaced apart and substantially paralleling each other together with a yoke-portion joining them, part of said yoke-portion being extended between the cheek portions toward their free extremities, and a part of the yoke-portion being inwardly extended in the form of a tongue and lying at an

acute angle to the plane of the same and directed toward a plane in which corresponding edges of the cheek portions lie, the free extremity of one of the cheek portions being recurved upon itself in open loop form, the other cheek portion in a part of its length being inwardly turned laterally thereof toward the recurved cheek portion.

2. In a receptacle for hearth tools, the combination of a supporting base having tool-receiving sockets therein; a top closure spaced above said base and having openings therethrough, said openings being each aligned above one of said tool-receiving sockets; a vertical partition of ribbon-like sheet form disposed between said base and top closure, said partition being generally U-shaped in plan and having its top and bottom edges abutting said top closure and base, respectively, the arms of the U of said partition each extending adjacent to one of said tool receiving sockets of said base and forming a guideway to direct a tool into said socket as the tool is inserted into the receptacle through said top closure, and means connecting said base and top closure and clamping said base and top closure against the bottom and top edges of said partition.

3. In a receptacle for hearth tools, the combination of a supporting base having a plurality of tool receiving sockets, two of said sockets being spaced outwardly from the center of said base; a top closure spaced above said base and having openings therethrough, said openings being each aligned above one of said tool receiving sockets; a vertical partition of ribbon-like form disposed between said base and top closure, said partition being generally U-shaped in plan and having its top and bottom edges abutting said top closure and base, respectively, the arms of the U of said partition each extending adjacent one of said two sockets, one of said arms being recurved upon itself to form a tubular tool guideway surrounding one of said two sockets, the other arm being curved inwardly toward the first mentioned arm to provide a tool guideway extending about a portion of the other of said two sockets; means connecting said base and top closure and clamping said base and top closure against the bottom and top edges of said partition, and an outer enclosing jacket interposed between said base and top closure.

4. A receptacle constructed in accordance with claim 3, wherein the base of the U of said partition includes a tongue extending between the arms of the U of said partition downwardly toward said base for guiding a tool inserted through said top closure to a seating position in a third one of said tool-receiving sockets, said third socket being substantially embraced by said partition as a whole.

LEWEN R. NELSON.
